UNITED STATES PATENT OFFICE

97,494

DESIGN FOR A CLOCK CASE

Eugene J. Lux, New York, N. Y., assignor to
Warren Telechron Company, a corporation of
Massachusetts

Application September 26, 1935, Serial No. 58,721

Term of patent 14 years

To all whom it may concern:

Be it known that I, Eugene J. Lux, a citizen of Austria, residing at New York, in the county of New York, State of New York, whose post office address is 204 East Thirty-Ninth Street, New York, N. Y., have invented a new, original, and ornamental Design for a Clock Case, of which the following is a specification, reference being had

to the accompanying drawing, forming a part thereof. The figure is a front perspective view of a clock case showing my new design.

I claim:

The ornamental design for a clock case as shown.

EUGENE J. LUX.
